CLAIM

The ornamental design for a bottle drainer rack, substantially as shown and described.

DESCRIPTION

FIG. 1 is a front elevational view of a bottle drainer rack showing my new design, the opposite side being a mirror image, shown in broken lines for illustrative purposes only;

FIG. 2 is a left side elevational view thereof;

FIG. 3 is a top plan view thereof;

FIG. 4 is a bottom plan view thereof; and

FIG. 5 is a right side elevational view thereof.

Fig. 1.Fig. 2.Fig. 3.Fig. 5.Fig. 4.
